UNIT PANEL REMOVABLE FLOOR FORM
FOR JOIST CONSTRUCTION

Fred Jarboe, San Diego, Calif.

Application February 16, 1932, Serial No. 593,274

2 Claims. (Cl. 25—131.5)

My invention relates to unit panel removable floor form for joist construction, and the objects of my invention are:

First, to provide a form of this class which is particularly adapted for the construction of concrete floors and ceilings;

Second, to provide a form of this class which eliminates the need of false ceilings inasmuch as the joist of the floor above may also be rendered ornamental thus reducing to a minimum the weight of the floor or ceiling constructed thereby.

Third, to provide a form of this class which may be readily and quickly constructed to meet the particular dimensions or architectural treatment of building in the construction of which the form is used;

Fourth, to provide a form of this class which may be removed without disturbing the temporary bracing, shoring or stringers used to support the form while the concrete is being poured, thus the form may be removed while the concrete is still green;

Fifth, to provide a form of this class which is particularly suitable in the construction of paneled ceilings, the form being capable of incorporating ornament or fresco forming members, and

Sixth, to provide on the whole a novel panel removable floor form for joist construction, which is durable, efficient in its action, and capable of being used repeatedly and which will not readily deteriorate or get out of order.

With these and other objects in view as will appear hereinafter, my invention consists of certain novel features of construction, combination and arrangement of parts and portions as will be hereinafter described in detail and particularly set forth in the appended claims, reference being had to the accompanying drawings and to the characters of reference thereon which form a part of this application, in which:

Figure 1 is a fragmentary perspective view showing my novel floor form in position after the concrete has been poured, and also showing the manner in which temporary bracing may be used in conjunction therewith; Fig. 2 is a fragmentary plan view of my floor form as it appears when positioned but before concrete has been poured; Fig. 3 is a fragmentary view of one corner portion of a floor form unit in which a fresco or ornament forming member is incorporated; and Fig. 4 is a transverse sectional view of said unit taken substantially through 4—4 of Fig. 3.

Similar characters of reference refer to similar

parts and portions throughout the several views of the drawings.

Joist bottom members 1 and 2, form side members 3 and 4, top piece 5, top plate 6, cleat 7, brace 8, cross members 9, cleats 10, and fresco forming member 11, constitute the principal parts and portions of my novel floor form.

Before positioning my novel floor form, conventional side wall forms A are positioned and shoring B, stringers C, and centering means or ledgers D are positioned, as shown in Fig. 1. The various elements of my novel floor form are then in position so as to be supported by the frame work comprising the aforementioned members.

Joist bottom members 1 are positioned along each ledger D. These members are in the form of flat strips with beveled side portions, indicated by 1a. The joist bottom members are positioned with their wider sides uppermost. These sides are somewhat wider than the ledgers upon which the bottom members rest. Wherever cross beams are to be provided, other joist bottom members 2 are placed, these members extending transversely with respect to the ledgers and are supported by any suitable means. The joist members 2 are provided with beveled side portions 2a similar to the beveled side portions 1a of the joist bottom members 1.

The joist bottom members 1 and 2 when positioned delineate a plurality of rectangular or square areas which form the panels or units of the floor or floor and ceiling, or roof and ceiling, as the case may be. One unit of my novel removable floor form is used in the construction of each of these panels. Each floor form unit comprises side members 3 and end members 4. The outer sides of these members slope inwardly slightly, as indicated by 3a and 4a, respectively, so as to provide sufficient draft to permit easy removal of the form unit.

The upper side of the rectangular frame formed by two pair of side members is closed by a top piece 5. The top piece 5 is set within the side members so that its upper surface is substantially flush with the upper edges of said side members. The top piece 5 is preferably covered with a thin sheet of metal or fibre board forming a top plate 6. The margins of the top plate 6 extend into notches or channels provided in the inner upper margins of the side members. The top piece 5 is held in place by means of cleats 7 positioned along the inner sides of the side members.

The form unit is reinforced by a longitudinally extending centrally disposed brace 8 which fits

adjacent the under side of the top piece 5. In addition cross members 9 are provided at intervals. These members are disposed underneath the brace 8 and extend between the side members 3.

5 Each form unit is constructed so as to fit snugly within the rectangular space provided by two pair of joist bottom members 1 and 2 when the lower margins, designated 3b and 4b, of the form side members slightly overlap the beveled sides of the joist bottom members, as shown best in Fig. 1, forming tool receiving spaces F. Each form unit is held in place by cleats 10 temporarily secured to the sides of the ledgers D.

15 After the several form units are positioned and the reinforcing has been arranged, the concrete E is poured so as to cover the several form units, thereby forming floor portions E1, joist or girder portions E2, or the like. After the concrete has set sufficiently the cleats 10 are removed, whereupon the claw of a hammer or crowbar or any other suitable tool is inserted in the space F provided between the bevelled sides 1a of the joist bottom members 1 and the lower margins 3b of the form side members 3 so as to pry the side members downward. By reason of the bevel or taper of the form unit and particularly the greater bevel of the sides of the joist bottom forming members, only a slight downward movement of the panel unit is required in order to break the seal with the concrete and loosen the panel or form unit and permit its removal as a whole. Hence, the form unit is ready for further use without re-assembling.

35 It will be noted that the joist bottom members 1 and 2 remain in place after the form unit is removed. This enables the form unit to be removed while the concrete is still green as very little stress or strain is placed thereon as long as the joists are supported. After the concrete has set a sufficient time the shoring B, stringers C, ledgers D, and form bottom members are removed.

If it is desired to provide ornamentation in the various panels, this may be easily accomplished by suitable fresco casting members 11 positioned on top of the various top plates 6, as shown in Figs. 3 and 4. In this manner a base relief design of practically any motif may be formed.

50 It will be noted that the particular construction illustrated readily permits the various ele-

ments of the form to be constructed from wood. This enables the various elements to be milled in stock lengths, then be cut to suit the particular job. Hence, after the form is removed there is little or no finishing work needed other than painting, as all irregularities due to joints or connections in the form are eliminated.

5 Though I have shown and described a particular construction, combination and arrangement of parts and portions, I do not wish to be limited to this particular construction, combination and arrangement, but desire to include in the scope of my invention the construction, combination and arrangement substantially as set forth in the appended claims.

10 Having thus described my invention, what I claim as new and desire to secure by Letters Patent is:

15 1. In a form of the class described, a plurality of joist bottom forming members disposed so as to delineate a plurality of polygonal areas, said members being beveled along their sides and arranged with their wider surfaces uppermost, and rigid panel forms arranged to conform to and fit within said polygonal areas, the margins of 20 said panel forms overlapping the beveled sides of said joist bottom forming members, and forming therewith prying tool receiving spaces.

25 2. A form for concrete ceilings comprising, a plurality of joist bottom forming members disposed so as to delineate a plurality of polygonal areas, said members being beveled along their edges and arranged with their wider surfaces uppermost, a plurality of beams extending along said joist bottom forming members, and shoring for supporting the beams and said joist bottom forming members, a plurality of panels shaped to conform to the polygonal areas including downwardly diverging side walls engaging the edges of said joist bottom forming members, the 30 divergence of the side walls being less than the bevel of said joist bottom forming members, whereby said side walls engage the upper edge 35 corners only of the joist bottom forming members to form prying tool receiving spaces therebelow, and temporary supporting means for said panels attached to the beams and engaging the lower edges of said side walls, said panels being removable in toto upon removal of said supporting means without distributing the joist bottom 40 forming members, their beams or shoring.

45 50 FRED JARBOE.
